UNITED STATES PATENT OFFICE

144,937

DESIGN FOR AN AIRPLANE

Edgar Schmued, Los Angeles, Calif., assignor to
North American Aviation, Inc., Inglewood,
Calif., a corporation of Delaware

Application March 31, 1944, Serial No. 113,104

Term of patent 3½ years

(Cl. D71—1)

To all whom it may concern:

Be it known that I, Edgar Schmued, a citizen of the United States, residing in Los Angeles, in the county of Los Angeles and State of California, have invented a new, original, and ornamental Design for an Airplane, of which the following is a specification, reference being had to the accompanying drawings, forming part thereof:

Fig. 1 is a side elevational view of the airplane;

Fig. 2 is a top plan view of the airplane depicted by Fig. 1;

Fig. 3 is a front elevational view of the airplane depicted by Fig. 2;

Fig. 4 is a front perspective view of the airplane in flight; and

Fig. 5 is a bottom plan view thereof the propellers being omitted.

I claim:

The ornamental design for an airplane, substantially as shown.

EDGAR SCHMUED.
